UNITED STATES PATENT OFFICE.

GOTTLOB HONOLD AND ARNOLD ZÄHRINGER, OF STUTTGART, GERMANY, ASSIGNORS
TO THE FIRM OF ROBERT BOSCH, OF STUTTGART, GERMANY.

IGNITING MECHANISM IN INTERNAL-COMBUSTION ENGINES.

1,017,212.

Specification of Letters Patent.

Patented Feb. 13, 1912.

Application filed December 17, 1909. Serial No. 533,630.

To all whom it may concern:

Be it known that we, GOTTLÖB HONOLD and ARNOLD ZÄHRINGER, engineers, subjects of the German Emperor, and residents of 11-13 5 Hoppentaustrasse, Stuttgart, Germany, have invented certain new and useful Improvements in or Relating to Igniting Mechanism in Internal-Combustion Engines; and we do hereby declare the following to be a full, 10 clear, and exact description of the invention, such as will enable others skilled in the art to which it appertains to make and use the same.

Our invention relates to igniting mechanism in internal combustion engines and more especially to magneto-electric machines as usually employed for this purpose. In machines of this kind, as is well known in the art, the igniting spark is usually inaugurated by first short-circuiting the armature of the magneto and then suddenly interrupting the short circuit at the moment in which the spark is to be generated. But, as is also well known, in machines of this kind the explosion of the gaseous charge of the cylinder is not instantaneous, but from the moment in which ignition takes place until the development of the full gas pressure a certain time elapses the duration of which depends 20 upon the nature of the mixture and the dimensions of the cylinder. If the ignition is to take place at a certain phase in the revolution of the motor crank, usually the point of greatest compression, it follows that the 25 spark must be produced at points more and more in advance of each other as the speed of the motor is increased. Furthermore the electric tension at the terminals of the armature of the magneto machine varies between 30 zero and a maximum once in every half revolution of the armature and in order to obtain an energetic spark it is necessary that the interruption of the wire short circuiting the armature winding should be performed 35 at a moment when the terminal pressure is near its maximum. From these well known facts it follows that, in order to obtain a satisfactory adjustment of the moment of ignition suitable for all speeds of the motor, the 40 relative positions of the motor crank and of the magneto armature should be varied accordingly. Heretofore it was usual to couple the armature with the crank shaft of the motor by means of gear wheels or other positively acting transmitting means and in or-

der to obtain a shifting of the relative positions of these two elements in some cases the armature is mounted adjustably on its shaft or the pole-pieces of the magneto machine are mounted adjustably and are arranged to be adjusted by hand to suit different speeds of the motor. It has also been suggested to couple a centrifugal governor with the motor shaft and to control the relative position of the armature by means of intermediate mechanism interposed between the governor and the armature.

The object of our present invention is to provide a mechanism of this kind and the invention consists in placing on the shaft by which the rotation of the motor crank shaft is transmitted to the armature shaft a coupling in which a mass suspended so as to be movable by the centrifugal force generated by rotation is interposed between the driving and the driven member in such a manner as to produce a relative displacement of the two members corresponding to the speed of the driving shaft. Thus when the coupling is rotated the mass will shift its position under the influence of the centrifugal force and will thus vary the relative adjustment of the armature. The interrupter being positively driven by the latter, will thus be automatically operated at different phases of the crank shaft according to the speed of the latter and nevertheless in the same phase of the armature shaft.

In the drawings Figure 1 is a cross section through a coupling according to our present invention in a plane laid between the driving and driven member (on line 1-1 in Fig. 3), the coupling being in its normal position. Fig. 2 is a repetition of Fig. 1 the parts being shown in the relative position they assume during rotation. Fig. 3 is a longitudinal section on line 3-3 in Fig. 1. Figs. 4 to 6 are similar sectional views of a modification of our invention.

A is the primary or driving shaft which is supposed to be coupled with the crank shaft of the motor by means of positively acting connections as for instance by a suitable train of gear wheels not shown in the drawing.

B is the secondary or driven shaft which may preferably be the armature shaft of the magneto-electric machine. Rigidly fastened to the shaft A is a disk A₁ and a similar disk B₁ is placed opposite to it on

105

110

the end of the armature shaft B and is likewise rigidly keyed thereto. By means of springs D, D hung on pins d, d and engaging the outer ends of the pendulums C, C the latter are held in their normal position, shown in Fig. 1, as long as no force, such as for instance centrifugal force, overcomes the action of the said springs.

Figs. 1 to 3 illustrate an embodiment of our invention in which a supplementary disk G is mounted between the driving disk A₁ and the driven disk B₁ so as to be loosely rotatable with relation to the two shafts. This supplementary disk G is provided with pins g, g forming the pivots of two centrifugal pendulums C, C, carrying pins e, e. The latter are connected by links f, f to pins e₁ and b₁ fixed respectively on the driving disk A₁ and the driven disk B₁. Thus when the coupling is rotated the pendulum, coupled with the pin e₁ which remains stationary with respect to the crank-shaft, in swinging outwardly will act to displace the supplementary disk G with relation to the driving disk A₁, and the pendulum coupled to pin b₁ in swinging outwardly will act to displace the driven disk B₁ with relation to the supplementary disk G. Since both pendulums are arranged to produce these displacements in the same sense of rotation, the two displacements will be added to each other and the total effect may be greater in quantity according to the choice of dimensions.

Referring to Fig. 2 it will be seen that all parts are displaced relatively to each other as by a centrifugal force acting upon the mass of the pendulums C, C and thus overcoming the springs D, D. In order to better illustrate the effect of this action it is assumed in this figure that the primary or driving member of the coupling has not changed its position this member being supposed to be positively coupled with the crank shaft which may be considered as being the initial motor of the entire system.

In order to illustrate the effective change in the length of the connection between the primary and secondary members, and the consequent relative shifting of the driven member or of the pin b₁, their initial or normal position is indicated in each figure by means of a line composed of alternate “—” and “0” and their altered or abnormal position by a line composed of alternate “—” and “X”. In Fig. 2 it is seen that these two lines have separated from each other and inclose a definite angle corresponding to the outward displacement of the pendulums C, C and consequently also corresponding to the speed of the driving shaft A of the crank shaft of the motor.

Figs. 4 to 6 show a modification. In this case the pins e and b fixed in the driving and driven disks A₁ and B₁ respectively are

employed, their power arms carrying pivots c, c which are connected to each other by a single link f forming an intermediate member in this case. Their outer or weight arms are connected to each other by means of a single spring D. This is the modification of our invention to which we give preference in most cases, because it produces the desired action with the least number of parts and is most easily assembled. Its operation will be readily understood by reference to Fig. 5 in which the two pendulums are swung outward and the two pivots e and b are shown at a correspondingly greater angular distance from each other than in Fig. 4 which illustrates the normal position; and it will be seen that here, as in Figs. 1 to 3 the quantitative effect of the two pendulums is cumulative.

The two modifications specifically illustrated in Figs. 1 to 6 represent main types of possible embodiments of our present invention.

In the embodiment illustrated in Figs. 1 to 3 both pendulums are hinged on a supplementary disk and act upon the driving and driven disk respectively while in the embodiment illustrated in Figs. 4 to 6 one of the pendulums is hinged on the driving and the other on the driven disk and both act upon each other by being pivoted to the rigid link f which forms an intermediate member in this case.

We desire it to be understood that a large number of combinations can thus be made up by any expert person merely by permutation of the various pivots and driving and driven pins and that the nature of our invention is not affected thereby.

It will be observed that in each of the modifications above indicated and described there is a positive link connection between the primary or driving member A, and the secondary or driven member B, and that in each case the movement of the pendulums in response to centrifugal force changes the effective length of the connection and advances the secondary member and the rotor with respect to the primary member as the speed increases.

Having now particularly described and ascertained the nature of our said invention and in what manner the same is to be performed, we declare that what we claim is:

1. In speed responsive mechanism for driving and driven parts, a driving element, a driven element, a weighted member connected to each of said elements, pivots about which said members are adapted to swing outwardly in response to centrifugal action, and an intermediate member carrying said pivots; whereby the difference of angular position of the elements is cumulatively changed as the speed changes.

2. In speed responsive mechanism for

- driving and driven parts, a driving element, a driven element, a weighted member operatively connected from a point intermediate of its ends to each of said elements, pivots 5 about which said members are adapted to swing outwardly in response to centrifugal action, and an intermediate member carrying said pivots; whereby the difference of angular position of the elements is cumulatively changed as the speed changes.
3. In speed responsive mechanism for driving and driven parts, a driving element, a driven element, a weighted member connected to the driving element so as to swing 10 outwardly in response to centrifugal action, a weighted member connected to the driven element so as to swing outwardly in response to centrifugal action, and a connection between the weighted members, said connections being arranged in such manner that the difference of angular position of the driving and driven elements is cumulatively changed as the speed changes.
4. In speed responsive mechanism for driving and driven parts, a driving element, a driven element, a weighted member connected intermediate of its ends to the driving element so as to swing outwardly in response to centrifugal action, a weighted 25 member connected intermediate of its ends to the driven element so as to swing outwardly in response to centrifugal action, and a connection between the weighted members, said connections being arranged in such manner that the difference of angular position of the driving and driven elements is cumulatively changed as the speed changes.
5. In speed responsive mechanism for driving and driven parts, a driving element, a driven element, a weighted member connected intermediate of its ends to the driving element so as to swing outwardly in response to centrifugal action, a weighted 30 member connected intermediate of its ends to the driven element so as to swing outwardly in response to centrifugal action, and a connection between the ends of the weighted members, said connections being arranged in such manner that the difference of angular position of the driving and driven elements is cumulatively changed as the speed changes.
6. In speed responsive mechanism for driving and driven parts, a driving element, a driven element, a weighted member pivoted to the driving element so as to swing outwardly in response to centrifugal action, a weighted member pivoted to the driven element so as to swing outwardly in response to centrifugal action, and a connection between the weighted members, whereby the difference of angular position of the driving and driven elements is cumulatively changed as the speed changes.
7. In speed responsive mechanism for driving and driven parts, a driving element, a driven element, a weighted member pivoted intermediate of its ends to the driving element so as to swing outwardly in response to centrifugal action, a weighted member pivoted intermediate of its ends to the driven element so as to swing outwardly in response to centrifugal action, and a connection between the weighted members, whereby the difference of angular position of the driving and driven elements is cumulatively changed as the speed changes.
8. In speed responsive mechanism for driving and driven parts, a driving element, a driven element, a weighted member pivoted intermediate of its ends to the driving element so as to swing outwardly in response to centrifugal action, a weighted member pivoted intermediate of its ends to the driven element so as to swing outwardly in response to centrifugal action, and a connection between the ends of the weighted members, whereby the difference of angular position of the driving and driven elements is cumulatively changed as the speed changes.

In testimony whereof we affix our signatures, in presence of two witnesses.

GOTTLOB HONOLD.
